UNITED STATES PATENT OFFICE.

RICHARD R. MOFFATT, OF BROOKLYN, NEW YORK, ASSIGNOR TO THE VICE VERSA ELECTRIC LAMP COMPANY.

DESIGN FOR AN ELECTRIC LAMP.

SPECIFICATION forming part of Design No. 26,987, dated April 27, 1897.

Application filed January 2, 1897. Serial No. 617,841. Term of patent 14 years.

To all whom it may concern:

Be it known that I, RICHARD R. MOFFATT, a citizen of the United States, residing at Brooklyn, in the county of Kings and State 5 of New York, have invented and produced a new and original Design for Portable Electric Lamps, of which the following is a specification.

In the accompanying drawings, Figure 1 is 10 to a front view of my design, and Fig. 2 is a cross-section thereof.

The leading features of my design are two 15 similar cylindrical battery casings or vessels, a frame attached thereto, an incandescent- 15 light bulb and filament, and a concave, parabolic, or meniscus-shaped reflector, as shown in the accompanying drawings.

A A are two battery casings or vessels approximately cylindrical in shape.

20 B B are belts or bands surrounding the said casings.

C is a reflector, of the configuration shown,

placed in front of the two casings in the position shown in the drawings, and D is an incandescent-electric-light bulb located in 25 front of the central part of the reflector C and partly or wholly within the concavity thereof. The said casings A A may be provided with devices a a for removing and replacing electrodes, with conducting-wires b, 30 and with such other parts as may be deemed necessary for the operation of batteries contained within casings constructed according to my design without modifying the general design thereof, which is as above described. 35

Having thus described my design, what I claim is—

The design for a portable electric lamp substantially as herein shown and described.

RICHARD R. MOFFATT.
